Strong & Moody,

Rice Cleaner.

Patented Apr 26, 1833.

Theodore H. Strong and Marcus T. Moody
Letters Patent.

The Schedule referred to, in these Letters Patent, and making part of the same, containing a description in the words of the said Theodore H. Strong, & Marcus Moody Inventors of their improvement, in the machine for Hulling, Cleaning & polishing Barley, Rice &c. — To all persons to whom these presents shall come. We of known that We Theodore H. Strong house carpenter & joiner & Marcus T. Moody Cabinet maker both of Northampton in the County of Hampshire & Commonwealth of Massachusetts citizens of the United States of America have jointly invented a new and useful improvement in the mode of Hulling Cleaning & polishing of rice, Barley, Brown corn and other small seeds having a hard kernel, and difficult to separate from the hull or brach, and which they have denominated Strong & Moody's second improved Huller & polisher, and that the following is a full and exact description of the construction and operation of said machine and improvement, as improved and invented by us. This improvement consists of two flat, or mill stone shaped cylinders of any required diameter placed on a perpendicular shaft similar to the stones in a quist mill. The upper cylinder is made of cast iron, having a sheathing on the under side made of wood ^{the under cylinder is made of cast iron having a sheathing on the upper side made of wood} The under side of the upper cylinder, and the upper side of the lower one, are to be studded, clothed, or charged with coarse emery, or other silicious substance, or with small or other hard and vicious composition, firmly united to the surfaces of the cylinders, running against each other by strong glue or other cement. The upper cylinder is moved by an upright shaft to which it is applied, while the lower one is suspended on a platform of iron or brass is placed on the outer edge of the lower cylinder and made of

of metal or wood having an opening, an orifice through which the seeds are ejected after having passed through the cylinder. From this pair of cylinders the seeds are passed through a coarser & screen. & from thence into one or more pairs of cylinders (with intervening coarser & screens,) shaped precisely like the first pair above mentioned, but clothed charged or studded with strong card teeth, & with points of metallic wire set in leather or any other strong and elastic substance. From the last pair of the last mentioned cylinders, the seeds are to be passed through a coarser & screen. If a higher polish is required than is produced by the foregoing machinery, the seeds may be passed through another pair of cylinders precisely like the before mentioned, studded, charged or clothed with very firm and stiff bristles or hair, or with the skin of the dogfish, having an underlay of India rubber or other elastic substance. Or instead of the short or mill stone shaped cylinders above mentioned, a truncated cone and corresponding hollow cylinder may be substituted, clothed, charged, & studded as is before described and specified for the mill stone shaped cylinders. Method of operation. The seed to be cleansed, hullled or polished is to be passed from a hopper into the coarse cylinder first above mentioned, from thence into a coarser & screen, then into the pairs of card tooth clothed cylinders above mentioned with their intervening coarser & screens, from thence into the polishing cylinders above mentioned, and from thence into a finer & screen & bolt. The improvement claimed by the said Young & Moody in this application as herein specified and described, is the method of hulling, cleaning & polishing or furnishing of rice, barley, corn, & other small seeds having a hard kernel and difficult to separate from the hull or husk by means of short flat, or mill stone shaped cylinders or of truncated conical

surrounding in corresponding hollow cylinders, clothed, charged, or
studded on these corresponding surfaces, as above described,
and specified, with coarse iron, or other hard and tenacious sub-
stance, or with small, or other hard and tenacious composition,
firmly united to the surfaces of the cylinders, or of the
cones and cylinders, by strong glue, or other cement and adhesive
in connection, with other cylinders, or cones and cylinders,
clothed, charged, or studded with coarse teeth, pins or points
of metallic wire, with boar's hair, or skin of the dogfish,
as is known before described, and specified, and their claim
on this present invention, is, as an improvement on Strong &
Mooray's Butter Smutter & polisher which was secured to the
present applicant by Spelled Patent, from the United
States—dated, August 29th A.D. 1832— and also as an improve-
ment on Strong & Mooray's improved patent butter smut-
ter & polisher which was secured to the present applicants
by Spelled Patent from the United States, dated December
17th A.D. 1832—

In testimony that the above, is
a true specification of our said improvement and
joint invention, as above described, we have hereunto
set our hands at Northampton aforesaid, this twenty-
eighth day of February, in the year of our Lord, one
thousand eight hundred and thirty three—
